DESIGN FOR A SHAVING CUP

Stanley Klosinski, Detroit, Mich.

Application June 16, 1948, Serial No. 147,007

Term of patent 7 years

(Cl. D86—10)

To all whom it may concern:

Be it known that I, Stanley Klosinski, a citizen of the United States of America and resident of the city of Detroit, county of Wayne, and State of Michigan, have invented a new, original, and ornamental Design for Shaving Cups, of which the following is a specification, reference being had to the accompanying drawing, forming part thereof.

I claim:

The ornamental design for a shaving cup, as shown.

STANLEY KLOSINSKI.
